UNITED STATES PATENT OFFICE.

LUDWIG B. LARSEN, OF PORTLAND, OREGON.

BOND FOR TWO-MEMBERED CONCRETE BUILDING-BLOCKS.

941,080.

Specification of Letters Patent. Patented Nov. 23, 1909.

Application filed February 17, 1908. Serial No. 416,406.

To all whom it may concern:

Be it known that I, LUDWIG B. LARSEN, a citizen of the United States, and a resident of Portland, in the county of Multnomah and State of Oregon, have invented a new and useful Improvement in Bonds for Two-Membered Concrete Building-Blocks, of which the following is a specification, reference being had to the accompanying drawings as constituting a part thereof.

This invention relates to the present well known system of two-membered construction of concrete building blocks; in other words, to the system of concrete building-blocks made of two pieces, separated from each other by an intermediate air-passage, and the two members of which are integrally united by a metallic bond; and my invention has for its object to obtain a simply constructed, inexpensive and effective metallic bond by which to effect integral unity of said two members of the concrete blocks.

Obviously, the parts must be so arranged that the metallic bond and the concrete mass have a firm hold on each other. Heretofore, the general method of construction of said metallic bonds consisted in the use of metallic strips having apertures through which the concrete penetrated, forming an integral bridge through such openings and abutting against or locking, as it were, with the shoulder-edges of the metal encompassing said openings.

Since in all constructions of the nature referred to, the force of expansion and contraction has to be taken into account, it is desirable to distribute the consequent strain as much as possible; and, furthermore, said shoulder-edges, of the apertures mentioned, offering necessarily only a very narrow surface, the construction is not as perfect in this respect as desirable. To overcome these apparent defects, I make my metal bond with right-angle integral lips or flanges projecting laterally from the side-faces of my metallic bond-strips, to secure better hold than other bond-strips not so constructed, to effectively distribute the strain due to contraction and expansion; and yet imposing no additional expense over the old form of construction, in fact, my improved bonds being made with no greater effort than those of the prior type mentioned.

The method of accomplishing the purpose in mind is more readily seen by having ref-

erence to the drawings above referred to, in which,

Figures 1, 2, and 3 represent three different types of construction of my improved metallic bond, said types to be more specifically explained in the body of this specification; Fig. 4 shows the arrangement of my metallic bond, when to be used for uniting right-angle courses or corner blocks of a wall; Fig. 5 represents an end elevation of a two-membered concrete block embodying my improved metallic bond; Fig. 6 is a top view of the same type of block shown in Fig. 5; and Fig. 7 is a top view of a corner block.

The letters designate the parts described.

My bond is conveniently stamped out of a piece of sheet steel, and when of the type shown in Fig. 1, it consists of an oblong strip *a*, made with apertures *b*, *c*, at its ends, which apertures are obtained by cutting out therefrom portions *d*, *e*, which are then turned at right angles to the face of the strip, as shown, so as to constitute flange-like braces projecting from the main body. In practice the bond of the type shown in Fig. 1 is embedded in the concrete mass, as illustrated in Figs. 5 and 6, in the process of making such concrete blocks, the same as heretofore done.

Instead of making my bond of the type shown in Fig. 1, the same may be made of greater width, as in the type illustrated in Fig. 3, comprising a body portion *f*, of greater width than the body portion *a*, shown in Fig. 1, and so as to be adapted to have two courses of flange-braces *g*, *g'* and *h*, *h'*; said courses being arranged one above the other, and the said flange-braces *g*, *g'*, *h*, *h'* being turned in opposite directions. This type of construction may be preferred where great solidity and strength are to be obtained in the wall to be built of my improved concrete blocks; and is especially adapted for larger sized blocks.

The type of bond illustrated in Fig. 3 would be embedded in the concrete mass in the process of making the concrete blocks, the same as described concerning the type Fig. 1.

For extra heavy work, where still greater rigidity in construction is desired, a type of block construction as illustrated in Fig. 2 may be made. The same consists of a band-like body *i*, made of a single piece and

formed in rectangular shape, the ends meeting as at i' , thus being embedded, finally, in the center of the block; and said body, i , being made with a series of flange-braces j , obtained by cutting out rectangular portions 5 of the sides and turning the same at right angles to the body of the bond-strip, substantially the same as above described and shown.

10 Where right angle courses, or corners, in the wall construction is required, I use for such corner members a bond of the construction illustrated in Fig. 4, resembling in its general appearance the type illustrated in Fig. 1, and comprising a body k , having portions l cut out, so as to leave flange-braces m ; the body k being bent at the center so as to conform to a right angle figure, and the flange-braces m being preferably 15 arranged so as to project from the opposite sides thereof; and it is also to be noted that the apertures l and flanges m are provided both, at the ends of the body k and at the central bent portion thereof.

20 25 The method of embedding my corner bond, just described, in the members of the concrete block is illustrated in Fig. 7, which figure also shows an additional bond of the type illustrated in Fig. 1.

30 35 A bond of the type illustrated in Fig. 2 would be embedded in its concrete mass transversely substantially in the same way as described concerning the embedding of bonds of the type illustrated in Figs. 1 and 3. The physical advantages of a bond of the type Fig. 2, for the purpose specified, are manifest.

n, n' represent the members of a common two-part concrete building-block, and o, o' 40 the members of a corner concrete building-block. The apertures b, c , in the type illustrated in Fig. 1, the aperture j' , in the type illustrated in Fig. 2, the aperture h^2 , of the type illustrated in Fig. 3, and the apertures 45 l , of the type illustrated in Fig. 4, have the common purpose of allowing the concrete mass to form an integral bridge between the cement material encompassing the side-faces of the body of the bond, and thus 50 effecting a unit of construction of the blocks and their bonds as a whole; and the flanges projecting at right angles from the bond strips add rigidity to the body of the bond, allow the concrete material to take a firmer 55 hold, and provide for the distribution of any strain, that is, any outward pull or inward push exerted by my bond upon either one or both of the opposed faces of the two members of the concrete block; and said pro-

jecting flanges also serve to distribute the 60 strain imposed upon the members of the concrete block during the setting of the concrete mixture, and by thermal conditions.

While I have described my improved bond as made by stamping the same out of a piece 65 of sheet steel, yet, of course, I do not limit myself to such methods of manufacture, for the same may be a metal casting if convenient and economical to do so.

I claim:

1. The combination with a building block comprising two members arranged in spaced relation, of a bond connecting said members, said bond comprising a metallic strip formed near each end with an aperture, the material 75 cut from the strip to form the aperture being integral with the strip along one edge and being bent at right angles to the strip to form flanges, the strip being embedded in the block members at right angles to the adjacent faces thereof with flanges extending longitudinally of and wholly embedded in the members, the ends of the strip being embedded in the members so as to expose a portion of each aperture beyond the inner 85 face of the member, whereby to provide an unbroken face section of each member for a height corresponding approximately to the width of the aperture to avoid weakening the member at the point of application of the 90 strip.

2. The combination with a corner block including two members having connected right angled sections, the corresponding sections of each member being arranged in 95 spaced parallel relation, of a bond for the members including a right-angled strip formed with apertures adjacent each end and adjacent and on each side of the angle, the material cut from the strip being integral therewith along one edge to form flanges, the strip being embedded in the members with the flanges adjacent the angle of the strip embedded in one member and the flanges adjacent the ends of the strip 100 embedded in the other member, the respective portions of the strip embedded in the members being arranged to expose a portion of each aperture beyond the inner face of said member, whereby to provide an unbroken face section of each member corresponding approximately to the width of the 110 aperture.

LUDWIG B. LARSEN.
